SIGNAL LAMP AND ALARM BOX STANDARD

Wenzel W. Thom, Wichita, Kans., assignor of one-half to Cecil D. Jones, Wichita, Kans.

Filed July 14, 1966, Ser. No. 3,075

Term of patent 14 years

(Cl. D72—1)

FIG. 1 is a side elevational view of a signal lamp and alarm box standard showing my new design;

FIG. 2 is a top plan view thereof;

FIG. 3 is a cross sectional view taken on line 3—3 of FIG. 1; and

FIG. 4 is a cross sectional view thereof taken on line 4—4 of FIG. 1.

The broken line representation of a signal lamp and alarm box in FIGS. 1, 2, and 3 are for purposes of illustration only.

I claim:

The ornamental design for a signal lamp and alarm box standard, as shown and described.
